UNITED STATES PATENT OFFICE.

PATRICK J. HUNT, OF NEW BEDFORD, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed November 9, 1922. Serial No. 599,936.

To all whom it may concern:

Be it known that I, PATRICK J. HUNT, a citizen of the United States, and resident of New Bedford, in the county of Bristol and State of Massachusetts, have invented an Improvement in Feeler Mechanisms for Looms, of which the following description, in connection with the accompanying drawings, is a specification, like characters on the 10 drawings representing like parts.

This invention relates to feeler mechanisms for looms through the instrumentality of which the filling in the shuttle is replenished prior to complete exhaustion while the 15 loom continues to run.

Feeler mechanisms of various types have heretofore been contrived mainly with a view of insuring, on the one hand, a complete shot of filling in the shed on the last 20 flight of the shuttle prior to replenishment, and a minimum amount of waste on the ejected filling carrier. In one type of such mechanisms, such as shown and described in the Edward S. Stimpson Patent, No. 25 1,309,226, the feeler is mounted for movement in a direction longitudinally of the shuttle by the forward pressure upon it to call the change when the filling in the shuttle is substantially exhausted but prior 30 to complete exhaustion. To hold the feeler from movement longitudinally of the shuttle on a detecting beat when a working supply of filling is contained within the shuttle, the feeler has heretofore been provided 35 with teeth which engage and penetrate more or less the filling mass. This recurring contact and penetration of the filling by the teeth of the feeler on each detecting beat is liable to injure the filling and cause defective cloth to be woven, which is observable in the form of spots or zones particularly in some kinds of cloth. It has heretofore been proposed to avoid injury to the filling by providing the feeler with a yielding 40 or non-metallic tip without teeth, but in such cases the feeler has been mounted to extend rearwardly at right angles to the longitudinal axis of the shuttle and was locked in this position until unlocked by depletion 45 of the filling and was then moved sidewise by spring or other means. Such feelers, therefore, were of the measuring type and although the feeler would be moved laterally to call the change, such movement was

dependent on freeing the feeler by measuring the diameter of the filling in the shuttle either by the feeler or the relation of the feeler and its locking means with the resulting liability of objectionable waste of filling. 55

One of the objects of the present invention, therefore, is to provide a feeler mechanism having a "side-swi" feeler provided with an untoothed tip which engages and is frictionally held by the filling from partaking of its recurring tendency to move longitudinally of the shuttle on each detecting beat without injurious effect upon the filling. The untoothed tip has a smooth filling engaging surface which sinks into the 70 mass of filling without penetration, and a further object is to provide an auxiliary tip which will be called into action and will engage the filling with a positive hold in case the smooth untoothed tip fails to do so and 75 the feeler starts along the filling longitudinally of the shuttle.

The various features of the invention, its novel characteristics and combination of parts will be better understood from the 80 following description and accompanying drawings of one good practical embodiment of the invention and the true scope thereof will be pointed out by the claims.

In the drawings:

Fig. 1 is a perspective view of a portion of a loom with the present invention applied thereto;

Fig. 2 is a plan view of parts, showing more particularly the operation of the feeler mechanism when, on a detecting beat, a working supply of filling is present in the shuttle and the untoothed feeler tip holds the feeler from movement longitudinally of the shuttle; 90

Fig. 3 is a view similar to that of Fig. 2 but showing the operation of the feeler mechanism when the untoothed tip of the feeler fails to hold the feeler from movement longitudinally of the shuttle while 100 still there is sufficient filling to continue weaving; and

Fig. 4 is a plan view with parts broken away, showing the feeler having been moved in a direction longitudinally of the shuttle to call the change, the filling being substantially exhausted. 105

In the drawings, the loom frame 1 has

mounted thereon mechanism called into operation by movement of the feeler longitudinally of the shuttle to effect replenishment of filling when the filling is substantially exhausted. As shown, the loom frame 1 has the brackets 2, one at each side of the loom, but only one being shown, and each is provided with a bearing 3 for the usual transverse or rock shaft 4. Secured to and rising from the rock shaft is the arm 5 to which the actuator 6 is connected at 7. In accordance with the present invention, the actuator 6 will be moved frontwardly when the feeler calls the change and will cause the rock shaft 4 to be rocked to effect the replenishment of filling, in a manner well understood by those skilled in the art. The replenishing mechanism is not shown because the details thereof are well understood and they form no part of the present invention.

In the present instance, the actuator 6 has an end portion 8 pivoted to the actuator at 9, and the forward extending end thereof is normally out of the path of movement of an operating member 11 which may be formed as part of or connected to the usual cam follower. Pivottally connected to a bracket 12 secured to the loom frame at 13 is a bell crank lever 14 the end 15 of which underlies a finger 16 extending from the part 8. The bell crank lever 14 is connected to a transmitter 17 which in turn is actuated by the feeler to turn the bell crank lever 14 contra-clockwise when the feeler calls the change.

Mounted on the shipper stand 18 is a bracket 19 to which is adjustably secured the feeler stand 20 by means of a bolt 21 which may pass through a slot 22 formed in the feeler stand. The bracket 19 may be adjustably secured to the shipper stand 18 by the bolt 23.

The feeler is shown as of the inclined "sideswipe" type; that is, it is mounted to enter the shuttle and feel for the filling in a direction inclined to the longitudinal axis of the shuttle and may be, except as herein-after described, substantially the same as shown and described in the Stimpson Patent, No. 1,309,226.

The feeler stand has secured thereto the bracket 24 between which and the feeler stand is a rocking bearing 25 through an opening in which extends the stem of the feeler 26. At the rear portion of the feeler stand is a laterally movable slide 27 in a suitable guideway or bearing 28 formed on or secured to the feeler stand, and to one end portion 29 of the slide 27 is connected the transmitter 17. The slide 27 has an opening 30 through which the feeler 26 extends with permissive movement laterally to a normal extent as the feeler is moved frontwardly and partakes of its normal swinging move-

ment about the axis of the bearing block 25, the feeler being held from movement longitudinally of the shuttle by the filling as the lay beats up. A spring 31 interposed between the bridge 32 to which the feeler is secured and the bearing block 25 normally acts to hold the feeler in its rearward feeling position. All the parts thus far described may be constructed and arranged substantially the same as the corresponding parts in the Stimpson patent hereinbefore mentioned.

The lay 33 is of the usual character and is provided with the shuttle box 34, the front wall 35 of which is provided with an opening 36 through which the feeler may pass when the lay moves frontwardly on a detecting beat.

The shuttle 37 is of usual type and is provided with an opening in its side wall 38 which registers with the opening 36 in the front wall of the shuttle box when the shuttle comes to rest in the box, the construction being such that the feeler may pass through the coinciding openings in the front wall of the shuttle box and shuttle and engage the filling or filling carrier in the shuttle on a detecting beat. The filling carrier 39 is shown as a bobbin of usual character having the usual shuttle jaw engaging rings for holding it in the shuttle and permitting its ejection therefrom when the filling 40 has been substantially exhausted, but the invention may also be advantageously employed in connection with cops or other forms of filling carriers.

The feeler 26 has at its rear end portion a feeler tip 41 which is formed of non-metallic material and preferably leather or leathroid, and the filling engaging end of the tip 41 is untoothed to present to the filling engaged by it a smooth non-injurious contact.

The engaging face or surface 42 of the untoothed feeler tip 41 is curved in an arc longitudinally of the shuttle and the tip 41 is secured to the feeler 26 in the present instance by a pin or bolt 43. The construction is such that when a working supply of filling is in the shuttle on a detecting beat the untoothed smooth engaging surface of the feeler tip contacts with the filling and is caused to sink into the filling mass to a slight extent by the forward pressure against it and thereby normally hold the feeler from movement longitudinally along the filling by frictional engagement therewith.

By the construction and arrangement described, the feeler may be advantageously employed with various characters of filling, either cotton, wool or silk, without injurious effect upon the filling, as may occur when filling engaging teeth of filling penetrating members are carried by the feeler tip.

- To effectively guard against premature movement of the feeler longitudinally along the filling on a detecting beat and to positively hold the feeler from such movement 5 when a sufficient mass of filling is not contained in the shuttle to permit the smooth untoothed feeler tip to sink into the filling, an auxiliary feeler tip is employed in accordance with the present invention. The 10 auxiliary feeler tip comes into action and positively engages the filling with holding contact should the smooth untoothed or main tip of the feeler fail to frictionally hold the feeler from such movement.
- 15 The auxiliary feeler tip 44 is mounted upon and moves with the feeler. As shown, it comprises the threaded stem 45 which passes through a lug 46 extending from the feeler and is held in adjusted position by 20 the nuts 47, the construction being such that the auxiliary feeler tip may be adjusted relatively to the main untoothed feeler tip. The rear end portion 48 of the auxiliary feeler tip is provided with a series of teeth 49 25 which if they engage the filling will penetrate it sufficiently to effect a positive hold and prevent movement of the feeler in a direction longitudinally of the shuttle.
- When a working supply of filling is present 30 in the shuttle on a detecting beat, as indicated in Fig. 2, the main untoothed and non-metallic feeler tip 41 will engage the filling and effect frictional hold therewith by sinking to a more or less extent into the filling mass and normally hold the feeler from movement longitudinally of the shuttle. Under such normal working conditions the toothed end portion of the auxiliary feeler tip does not engage the filling, or if 35 such engagement occurs in any particular case, the teeth do not injuriously affect the filling because they do not penetrate, being held from such penetration or injurious contact by the already engaged smooth surface 40 of the non-metallic untoothed feeler tip 41. Should, however, the untoothed feeler tip 41 fail to hold the feeler from movement longitudinally of the shuttle on a detecting beat, the feeler will start along the filling, and 45 thereby bring into action the auxiliary feeler tip the teeth of which will effect a positive hold upon the filling and restrain the feeler from any further movement or movement sufficient to call a change.
- 50 When the filling in the shuttle approaches substantial exhaustion and there is not sufficient filling in the shuttle to permit the untoothed non-metallic feeler tip from sinking into the filling with a frictional hold thereon, the feeler will start to move longitudinally along the filling from the dotted line position, Fig. 2, to the full line position, such slight movement, however, not being sufficient to cause the feeler to move the slide 27 55 and effect replenishment, and thereupon the toothed end of the auxiliary feeler 44 comes into play as indicated in Fig. 2 and engages the filling with a positive hold.
- When, however, the filling has reached a condition of substantial exhaustion, as indicated in Fig. 4, even the toothed end portion of the auxiliary feeler fails to engage the filling with holding contact and by frontward pressure thereon the feeler will move in a direction longitudinally of the shuttle 75 and call for replenishment of filling.
- The untoothed, smooth and rounded engaging surface of the main feeler tip 41, therefore, acts normally to hold the feeler from movement longitudinally of the shuttle 80 by frictional engagement with the filling without injurious effect thereon. Indeed, it is found in practice that the frictional engagement of the main feeler tip with the filling without penetration thereof may be 85 advantageously employed with any kind of yarn or filling, even of delicate character, such as silk, for instance, and that the feeler, notwithstanding its tendency to move longitudinally of the shuttle on a detecting beat, 90 will be effectively restrained from such movement by frictional engagement until the filling approaches substantial exhaustion, whereupon the toothed auxiliary tip comes into action, as indicated in Fig. 2, to positively hold the feeler from movement longitudinally of the shuttle until on a detecting beat the filling is substantially exhausted and only sufficient remains to make the required number of picks and provide the 100 requisite tension for the filling.
- Filling bobbins wound with filling, as supplied from the spinning room, are sometimes defective in the wind, due to broken down ends or other causes. To meet this 105 condition the feeler of the present invention has adjustably mounted thereon a bunter 50 which passes through a lug 51 on the feeler and is held in adjusted position by the nuts 52. The bunter has a head 53. The bunter 50 under normal conditions of 110 weaving is adjusted frontwardly to such an extent that it does not come into operation either when using filling wound bobbins or cops. When, however, it is found that the spinning room is supplying defective bobbins or cops, the bunter may be adjusted rearwardly on the feeler to engage the side wall of the shuttle when the filling is merely 115 exhausted and cause the feeler to move longitudinally along the filling carrier by frontward pressure on the bunter. The bunter, however, is merely a precautionary expedient to meet the condition of defective bobbins furnished by the spinning room and is ordinarily adjustd frontwardly so as not to operate or engage the shuttle on a detecting beat whether there be little or more filling in the shuttle.
- In the construction and relation of the 120 125 130

main and auxiliary feeler tips, as shown, the former is provided with a recessed side portion 54 into which extends the laterally projecting toothed end 55 of the auxiliary feeler tip, and the toothed end portion of the auxiliary feeler tip is adjusted so as to be slightly forward of the untooothed, smooth engaging surface of the main feeler. This construction is advantageous for some purposes, but the invention, of course, is not necessarily restricted thereto.

What is claimed is:

1. In a feeler mechanism for looms, the combination of a feeler mounted to enter the shuttle on a detecting beat in a direction inclined to the longitudinal axis of the shuttle and provided with an untooothed non-metallic tip which sinks bodily into the filling and by frictional engagement therewith prevents movement of the feeler longitudinally along the filling carrier until the filling approaches substantial exhaustion, and an auxiliary feeler tip mounted upon the feeler in non-contacting relation to the filling on a detecting beat until the untooothed non-metallic tip is displaced longitudinally along the filling carrier by the forward pressure upon it and then engaging the remaining portion of the filling and holding the feeler from movement longitudinally along the filling carrier until the filling is substantially exhausted.

2. In a feeler mechanism for looms, the combination of a feeler mounted to enter the shuttle on a detecting beat in a direction inclined to the longitudinal axis of the shuttle and provided with an untooothed non-metallic tip having a curved filling engaging surface which sinks bodily into the filling and by frictional engagement therewith prevents movement of the feeler longitudinally along the filling carrier until the filling approaches substantial exhaustion, and an auxiliary feeler tip mounted upon the feeler in non-contacting relation to the filling on a detecting beat until the untooothed non-metallic tip is displaced longitudinally along the filling carrier by the forward pressure upon it and then engaging the remaining portion of the filling and holding the feeler from movement longitudinally along the filling carrier until the filling is substantially exhausted.

3. In a feeler mechanism for looms, the combination of a feeler mounted for movement in a direction longitudinally of the shuttle to call the change of filling and having a main untooothed filling engaging tip which by frictional engagement with the filling on a detecting beat prevents movement of the feeler longitudinally along the filling carrier until the filling approaches substantial exhaustion, an auxiliary feeler tip mounted upon and movable with the feeler to engage the

filling in the shuttle on a detecting beat in case the main untooothed feeler tip fails to hold the feeler from movement longitudinally of the filling carrier as the lay beats up on a detecting beat, and means for effecting replenishment of filling when neither tip holds the feeler from movement longitudinally of the filling carrier.

4. A loom feeler mechanism having a side swipe feeler provided with a main untooothed tip which nominally engages the filling on a detecting beat and frictionally holds the feeler from movement longitudinally along the filling, and an auxiliary feeler tip mounted on the feeler to engage the filling in the shuttle on a detecting beat only when the main untooothed tip moves longitudinally of the shuttle.

5. A loom feeler mechanism having a feeler mounted for movement in a direction longitudinally of the shuttle and provided with a main untooothed frictional holding tip which normally engages the filling on a detecting beat, and an auxiliary tip mounted on the feeler at one side of the main untooothed tip to engage the filling in the shuttle and prevent premature movement of the feeler longitudinally of the shuttle when the frictional hold of the main untooothed tip with a working supply of filling fails to do so.

6. A loom feeler mechanism having a laterally movable feeler provided with a main leather tip which normally engages the filling on a detecting beat and frictionally holds the feeler from movement longitudinally along the mass of filling, and an auxiliary tip secured to the feeler and provided with teeth to engage the filling should the main leather tip fail to hold the feeler from movement along the mass of filling.

7. A feeler mechanism having a feeler with a main untooothed tip presenting a smooth surface curved in a direction longitudinally of the shuttle for frictional holding engagement with the filling on a detecting beat, and an auxiliary feeler tip secured to the feeler alongside of the main untooothed tip for holding engagement with the filling should the frictional engagement of the main untooothed tip with the filling fail to hold the feeler from movement longitudinally of the filling carrier.

8. A loom feeler mechanism having a feeler mounted for movement in a direction longitudinally of the shuttle and provided with a main untooothed frictional holding tip which normally engages the filling on a detecting beat, and an auxiliary tip mounted on the feeler at one side of the main untooothed tip to engage the filling only in case the main tip prematurely slips along the filling, and means for relatively adjusting the two tips.

9. A feeler mechanism for looms having

a feeler mounted to enter the shuttle in a direction inclined to the longitudinal axis of the shuttle and provided with a main nonmetallic frictional holding tip which sinks into but does not penetrate the filling mass on a detecting beat, and an auxiliary feeler tip mounted on the feeler at the side of the main tip and having teeth which engage the filling when the main frictional holding tip fails to hold the feeler from movement longitudinally of the shuttle due to the forward pressure against it on a detecting beat.

10. A feeler mechanism for looms having a feeler to enter the shuttle in a direction inclined to the longitudinal axis of the shuttle and to be displaced laterally by the forward pressure when the filling is substantially exhausted on a detecting beat, a tip carried by the feeler and inherently capable in its operative relation of gripping yarn on a filling carrier in the shuttle without penetrating therein but adapted to slip when it

encounters a smooth and substantially unyielding surface on a detecting beat, said tip being subjected to the full impact of the filling throughout its detecting action.

11. A feeler mechanism for looms having a feeler to enter the shuttle in a direction inclined to the longitudinal axis of the shuttle and to be displaced laterally by the forward pressure when the filling is substantially exhausted on a detecting beat, a leather tip carried by the feeler and inherently capable in its operative relation of gripping yarn on a filling carrier in the shuttle without penetrating therein but adapted to slip when it encounters a smooth and substantially unyielding surface on a detecting beat, said tip being subjected to the full impact of the filling throughout its detecting action.

In testimony whereof, I have signed my name to this specification.

PATRICK J. HUNT.
